UNITED STATES PATENT OFFICE.

EARL A. AVERILL, OF MOUNT VERNON, NEW YORK, ASSIGNOR TO LOCOMOTIVE FEED WATER HEATER COMPANY, A CORPORATION OF DELAWARE.

FEED-WATER HEATER.

Application filed November 4, 1920. Serial No. 421,642.

To all whom it may concern:

Be it known that I, EARL A. AVERILL, a citizen of the United States, residing at Mount Vernon, in the county of Westchester and State of New York, have invented certain new and useful Improvements in Feed-Water Heaters, of which the following is a specification.

This invention relates to feed water heaters for locomotives and the like and has for one of its primary objects the provision of an improved multi-pass heater in which the passes for the water to be heated are so arranged that the colder passes are at the bottom and the hotter passes at the top, an arrangement which, for reasons hereinafter pointed out, greatly increases the efficiency of the heater.

Another of the objects of the invention resides in the provision of an improved heater in which the steam distribution is more uniform so that temperature conditions and, therefore, expansion will be more uniform in the various parts.

My invention also contemplates certain detail improvements and combination of parts in the heater arrangement, hereinafter more fully to be pointed out.

In general, I propose an improved heater of simple construction and efficient in operation, the parts of which may be readily assembled and taken apart.

The foregoing, together with such other objects as may hereinafter appear, I obtain by means of a construction illustrated in preferred form in the accompanying drawings, wherein:

Fig. 1 is a longitudinal section on the line 1—1 of Figures 3 and 4 through a heater embodying my improvements; Fig. 2 is an end elevation of Fig. 1; Fig. 3 is a section taken on the line 3—3 of Fig. 1; Fig. 4 is a section taken on the line 4—4 of Fig. 1.

Referring now to the drawings, it will be seen that the device includes an open-ended cylindrical casing 7, provided with two oppositely arranged inlets 8 at the top for connection with the exhaust passages in the saddle casting or with the steam chest exhaust ports, and with a drain 9 at the bottom. The ends of the casing 7 are closed by the tube plate 12 at one end and the casing cap 11 at the other end. The heating elements consist of the tubes A, preferably arranged in four passes respectively num-

bered 1, 2, 3 and 4 (see Fig. 3); the stationary tube plate 12 secured to one end of the casing 7; the floating tube plate 13; and the headers 14 and 15. The headers are secured to their respective tube plates by the stud bolts 16 at the periphery and by the studs 17 at the center. The studs 17, which serve to draw the tube plates 12, 13 against the header septa hereinafter referred to, are not directly connected to the tube plates but are threaded in the sockets 18 which in turn are threaded to the tube plates. These sockets 18 can be made of a non-corrosive metal that will resist the action of the steam and by reason of the fact that they can be applied before the parts are assembled they can be threaded finer and better secured to the tube plate. This arrangement makes it more feasible to obtain a steam-tight or leak-proof connection which extends the life of certain of the parts which would otherwise be more rapidly worn out. Suitable gaskets 19 are provided between the headers and the tube plates. It will be understood that the headers are provided with septa dividing them into the proper number of compartments to secure the desired number of passes. The header 14 is provided with an inlet 20 to pass 1 and with an outlet 21 from pass 4. The casing end cap 10 is secured against the tube sheet 12 over the header 14 by means of stud bolts 16* in the outer side of the header 14, and is thus readily removable to give access to the outer ends of the bolts 17 extending through the header 14 from the tube plate 12.

A baffle plate 22 secured to the tube plates 12 and 13 above the tubes extends from header structure to header structure in the line of the incoming steam admitted from opposite ends of the casing through the superjacent inlets 8 in order to prevent such steam from directly impinging upon the upper tubes. Two guard plates 23 are secured to the tube plates at a point below the lowermost tubes and serve to protect the latter when the heating elements are slid into or out of the casing.

It will be seen from the foregoing that in operation water is introduced through the inlet 20 and traverses the tubes of pass 1 to header 15, from which it returns to header 14 through the tubes of pass 2, after which it passes upwardly in the header 14 to the tubes of pass 3, returning to such header

through the tubes of pass 4, after which it is discharged through the outlet 21 to the boiler. It will thus be seen that the coldest water is in the bottom of the heater which is an advantage of great importance for the reason that a very large percentage of the steam is condensed by the colder tubes of the first two passes, and if these be located at the top, as is customary, the condensation drips on to the lower tubes cutting down their efficiency. By the improved arrangement, however, by far the greater part of the condensate is formed on the lower two passes and the upper passes containing the hotter water will have maximum efficiency. The baffle 22 also secures a more even distribution of the incoming steam throughout the heater which also tends to promote efficiency and to maintain more uniform temperature and, therefore, more uniform expansion conditions.

It will also be seen that the heat transfer member formed by the tubes A, tube plate and header structures 12, 14 and 13, 15 and the associated parts constitutes a complete water circulation unit, and is readily removable as a structural unit as soon as its water inlet and outlet connections are disconnected and its securing bolts 16 released. It will be seen that the tube plate and header structures of this water circulation unit are connected and spaced apart, independently of any of the tubes A extending between them, by the longitudinal members

22 and 23. These members 22 and 23 are 35 freely exposed to the steam in the casing 7, and leave the tubes A freely exposed.

I claim:

1. In a feed water heater, the combination of a heater casing, and a heat transfer member removable as a unit and comprising a pair of tube plates and a plurality of tubes secured in said plates, means for detachably securing the said member to the casing, and guard means extending longitudinally of 40 and beneath the tubes for protecting the same upon insertion and removal of said member from the casing.

2. In a feed water heater, the combination of a casing, a pair of tube plates, a plurality of tubes, a header for each tube plate, a socket threaded in each tube plate, and bolt-like means for securing the headers to the respective tube plates threaded in said 50 sockets.

3. A feed water heater comprising an open-ended casing; and a removable water circulation unit therefor including tube plate and header structures, water tubes extending between said structures, and longitudinal guard means for protecting the tubes during removal or insertion of the unit from or in the casing rigidly secured to said structures beneath the lowermost tubes.

In testimony whereof, I have hereunto 60 signed my name.

EARL A. AVERILL.
